MATTRESS

Filed Nov. 24, 1926

UNITED STATES PATENT OFFICE.

VAUGHN D. MULKEY, OF OAKLAND, CALIFORNIA.

MATTRESS.

Application filed November 24, 1926. Serial No. 150,395.

The present invention relates to improvements in mattresses and its particular object is to provide in combination with a mattress a handle interwoven with the mattress cover or ticking in such a manner that manipulation of the handle effects the mattress throughout the cross-sectional extent thereof and is not limited to a local section of the mattress. It is particularly proposed in this connection to use for a handle a strip of material encircling the entire mattress and being disposed on the inside of the top and bottom cover of the mattress and on the outside at the side edge thereof. It is a further object of the invention to effect the transition from inside to outside at the seams so the material of the cover itself remains unaffected and is not weakened by passing the strip therethrough. Further objects and advantages of my invention will appear as the specification proceeds.

The preferred form of my invention is illustrated in the accompanying drawing in which—

Figure 1 shows a perspective view of a mattress having my handle attached thereto, Figure 2 a vertical section through a corner of the mattress before the edge is rolled, and

Figure 3 a similar section showing the corner after the edge is rolled.

While I have shown only the preferred form of the invention, I wish to have it understood that various changes or modifications may be made within the scope of the claim hereto attached without departing from the spirit of the invention.

The mattress 1 comprises the ticking 2, the stuffing 3, and the cover 4 surrounding the entire mattress. The cover forms the particular subject matter of the present invention although it should be understood that the feature of the handle might be incorporated in the ticking without departing from the spirit of the present invention. A strip of material 6 is arranged relative to the cover so as to encircle the entire mattress and to thereby reinforce the same. That portion of the strip designated by the numeral 7

and lying adjacent the top and the bottom of the cover is disposed on the inside thereof, while the portion 8 along the side of the cover projects to the outside and forms a convenient handle for manipulating the mattress. The transition from the inside to the outside takes place at the seam 9 as illustrated in Figure 2 from which it will be seen that the material of the cover itself is not affected in any way by the transition of the strip from the inside to the outside so that there is no weakening of the material at any spot. When the edges of the mattress are rolled in the manner shown in Figure 3, a portion of the cover, the ticking, and the stuffing is separated from the main body section of the mattress and the strip accompanies the material of the cover.

At the top and bottom of the mattress, the strip 7 is preferably sewed to the cover while the section 8 forming the handle is free of the cover. It should be understood, of course, that while the strip 7 is described in this specification as a continuous strip, it is not necessary that the same be made of one piece throughout the extent thereof, and it might be preferable to use different material for the strip along the top and bottom edges from that used along the sides. It is important, however, that there be such continuity in the strip that handling of the handle 8 will make itself felt around the entire mattress.

I claim:

A mattress comprising a stuffing, a cover having its marginal edges formed into rolls, a relatively narrow strip completely encircling said stuffing, said strip being attached to the inside of said cover along the top and bottom of said mattress between the formations of said rolls at the edges, said strip being disposed through openings formed in the seams of said cover and passing thereby freely in the formation of said rolls from the inside of the cover to the outside of the same along the sides of the mattress to form a handle.

In testimony whereof I affix my signature.
VAUGHN D. MULKEY.
